UNITED STATES PATENT OFFICE.

OLAF HETLESAETER, OF MILWAUKEE, WISCONSIN.

EXCAVATOR.

No. 895,459.

Specification of Letters Patent.

Patented Aug. 11, 1908.

Application filed September 18, 1907. Serial No. 393,503.

To all whom it may concern:

Be it known that I, OLAF HETLESAETER, a citizen of the United States, residing at Milwaukee, in the county of Milwaukee and State of Wisconsin, have invented a certain new and useful Improvement in Excavators, of which the following is a specification.

My invention relates to improvements in excavators of the general class embracing the machines described in the following Letters Patent of the United States heretofore granted to me: No. 649,244, issued May 8, 1900; No. 649,408, issued May 8, 1900; No. 659,632, issued Oct. 9, 1900; No. 665,683, issued Jan. 8, 1901; No. 665,685, issued Jan. 8, 1901; No. 667,315, issued Feb. 5, 1901; No. 669,992, issued Mar. 19, 1901; No. 669,991, issued Mar. 19, 1901; No. 868,267, issued Oct. 15, 1907.

20 This present invention in a certain sense embodies improvements over the invention shown in the last mentioned patent.

The general object of the present invention is to provide an excavator which is simple and positive in its action and capable of continuous operation without the necessity of swinging the bucket laterally between each digging movement.

As supplementary to this latter characteristic it is an object to provide a supplemental or receiving bucket adapted to receive the excavated material in the digging bucket and to forward said material to a hopper or other receptacle from which the excavated material may be finally removed. I obtain these objects by the mechanism illustrated in the accompanying drawings, in which:

Figure 1 is a general side view of the machine showing the digging bucket in digging position. Fig. 2 is a similar view showing the digging bucket in discharging position. Fig. 3 is a plan view of the machine with the parts in the position shown in Fig. 1. Fig. 4 is a side view of the lower portion of the machine with the framework broken away in order to reveal the gearing by which the bucket and bucket arm may be swung laterally. Fig. 5 is a plan view of the parts shown in Fig. 4. Fig. 6 is a diagrammatic view showing the relationship of the main parts which support the digging and receiving buckets.

In the preferred form of machine, shown, the main oscillating member 1 is pivotally

supported by a shaft 2 mounted in a suitable portion 3 of the framework of the machine. This member is operated by means of connecting rods 4 operated by the crank arms 5, which preferably constitute an integral portion of the master gears 6, said master gears being driven by any suitable gearing 7 and power device 8. The digging member 9 is suspended from the oscillating member 1 by means of the links 10 and is controlled, that is, thrust toward or retracted from the bank of earth by means of the controlling members 11. By preference members 11 constitute an integral portion of the gears 12 which are operated by the pinions 13. Said pinions 13 are rigid on a shaft 14 which is driven by any suitable gearing 15 and controlled through the clutch mechanism 16. For convenience both the master gears 6 and the controlling gears 12 are mounted upon the same shaft 17. The controlling gears 12 are loose upon said shaft, as indicated in Fig. 5, and their movement therefore is independent of the rotary movement of the master gears 6.

The manner of the operation of the above described parts is as follows: The power device 8 having a continuous rotary movement drives the master gears 6 with a continuous rotary movement which causes a continuous oscillatory movement of the oscillating member 1. This causes a continuous hoisting and lowering of the digging member 9 from the position for example shown in full lines Fig. 1 to the position shown in Fig. 2. The depth of the cut is regulated by the operator who throws in the clutch mechanism 16 in the manner desired by him, either in the forward or reverse direction, thereby controlling the position of the members 11 which are articulately connected to the digging member 9. The position of the digging member laterally is determined by the gearing 18 located preferably beneath the revolving platform 19 as best shown in Fig. 4. It will thus be seen that the parts described constitute a complete excavating apparatus excepting the means for removing from the digging member the material excavated by it. An important characteristic of the machine is that the digging member oscillates about a fixed axis through an arc less than a complete circumference, that the reversal in direction of motion of the digging member is automatic and that the oscillatory motion is

continuous. In this respect the present machine is like the machine shown in my Patent No. 868,267, issued October 15, 1907.

Although different means may be employed for removing the excavated material from the digging member, I prefer to employ a supplemental bucket 20 constructed in the manner illustrated in the drawings. In the design here shown this supplemental bucket 10 is rigidly secured to an arm 21 pivoted to the framework of the machine at the shaft 22. This arm 21 is operated by means of a rod 23 connected to the inner extremity of the oscillating member 1.

By reference to Figs. 1 and 2 it will be clear that in operation when the digging member 9 is hoisted to the position shown in Fig. 2, the receiving bucket 20 will be in position to receive material therefrom and when the digging member 9 is lowered to the digging position shown in Fig. 2 the receiving bucket will be elevated to the discharging position from dumping its contents into the hopper 24 or whatever receptacle is provided. The supplemental or receiving bucket being connected to and operated by the parts which operate the digging member, it is of course clear that the parts will operate in timed relation, automatically, and will therefore require no attention on the part of the operator. The receiving bucket will receive the contents of the digging member and will then discharge said contents while the digging member is acquiring a new load.

It will be noted that while the receiving bucket 20 is being raised the digging member 9 is being lowered, and that while the receiving bucket is being lowered the digging member 9 is being raised. The result is that the machine takes advantage of the weight of the descending member for assisting in the elevation of the ascending member. There is consequently a counterbalancing effect between the digging and receiving members of the machine and as a result less power is required to operate it than would be required if the parts were not thus counterbalanced.

It is desirable to provide means for insuring complete delivery of the load from the digging member to the receiving bucket and hence it is desirable to employ in the digging member a bucket 25, which, in the present instance is hinged upon the pin 26 in the digging member 9 and has a rear extension 27 which comes to be struck by the receiving bucket 20 as indicated in Fig. 2. As is shown, the striking of the bucket 20 upon the rear extension 27 of the bucket 25 causes said bucket 25 to tilt backwards and forcibly eject its contents into the bucket 20. The shock or jar incident upon this impact tends to loosen any material such as clay, which might otherwise have a tendency to adhere to the bucket 25.

It is desirable that means be provided for preventing the digging member 9 and controlling member 11 from straightening out beyond center. In the present design this purpose is accomplished by means of the chain 29 which is fastened at one end to said digging member and at the other end to said controlling member.

What I claim as new and desire to secure by Letters Patent, is:

1. An excavator having a digging member adapted to oscillate about a fixed horizontal axis, and means for rotating said digging member about said axis through an arc less than a complete circumference and automatically reversing the direction of rotation of said digging member.
2. An excavator comprising a digging member, an oscillating member connected thereto for raising or lowering it, a crank connected to said oscillating member for oscillating the same, and means including a toothed gear for thrusting and retracting said digging member.
3. An excavator comprising a digging member, an oscillating member linked thereto for lowering and hoisting it, a crank connected to said oscillating member for oscillating it, means for continuously rotating said crank and controlling means including gearing and a power device for operating it for thrusting and retracting said digging member.

4. An excavator comprising a digging member, an oscillating member linked thereto for lowering and hoisting it, continuously operating means for oscillating said oscillating member, and a receiving bucket for receiving and removing the contents of said digging member; said receiving bucket being connected to and operated by the means which operate the digging member.

5. An excavator comprising a framework and digging member, an oscillating member connected thereto for lowering and hoisting the same, means for operating said oscillating member, means for thrusting and retracting said digging member, and a receiving bucket pivoted to the framework of the machine and connected to and operated by said oscillating member for automatically receiving the contents of said digging member and discharging said contents at a distance.

6. An excavator comprising a digging member, continuously operating means for raising and lowering it, and a bucket carried by said digging member, said bucket being pivoted to said digging member for facilitating the discharge of excavated material.

7. An excavator comprising a digging member, continuously operating means for raising and lowering it, a bucket carried by said digging member, said bucket being piv-

oted to said digging member for facilitating the discharge of excavated material, and a receiving bucket for receiving and removing the contents of said digging member, said 5 receiving bucket being adapted to contact said digging bucket and tilt the same for emptying it.

In witness whereof, I have hereunto subscribed my name in the presence of two witnesses,

OLAF HETLESAETER.
